WALL CLOCK

Ostilio Ciccarelli, Bristol, Conn., assignor to The
E. Ingraham Company, Bristol, Conn., a cor-
poration of Connecticut

Application April 6, 1939, Serial No. 266,310

6 Claims. (Cl. 58—56)

The present invention relates to improvements in wall clocks, and particularly to that type of wall-clock structure having supporting-means especially constructed and arranged and organized therewith for supporting wall clocks adjacent to walls and, preferably, substantially flat against walls.

One of the objects of the present invention is to secure wall clocks of superior construction and organization, in which strain in a device projected from a wall to hold a clock, and in supporting-means engaging the holding-device and secured to and forming part of a wall clock, is minimized; whereby marring or breaking-out of a wall under pull on the holding-device, and loosening of the said supporting-means with respect to the clock, are substantially avoided, to provide dependable and safe support for a clock on a wall at the customary substantial height above the floor level.

A further object of the present invention is to provide improved wall clocks having a structure of superior supporting-stability for supporting a clock on a wall in stationary or motionless relation thereto, to substantially eliminate tilting of a clock about a holding-device therefor projecting from a wall, and to eliminate or minimize shimming of a clock with respect to a wall, and knocking of a clock against a wall, because of vibrations that may be set up in a clock, particularly an electric clock, or because of vibrations occurring in a wall, or like causes.

Another object of this invention is to secure improved wall clocks in which supporting-means for supporting a clock on a wall is organized in nested relation to the clock-structure, and is substantially enclosed and shielded by the said clock-structure, to provide for supporting the clock on, and substantially flat against, a wall, and to further provide effective protection of the supporting-means against damage, and also to substantially avoid possible dislodging of the clock from the wall.

Still another object of this invention is to secure improved wall clocks, as described, and having a supporting-structure therefor arranged in substantially enclosed relation and concealed from view, superior construction and arrangement of the said supporting-structure, whereby wall clocks may be readily, conveniently and securely brought into position and supported on walls.

A still further object of the present invention is to provide wall clocks of superior construction and arrangement, for which supporting-means of improved nature may be easily produced and

secured in place with respect to the clock-structure and, therefore, at low cost; the said construction and arrangement, particularly of the said supporting-structure, providing a compact and sturdy organization, whereby wall clocks may be reliably supported on walls at substantial heights above floor levels, and also present desirably good appearance in place on walls.

With the above and other objects in view, as will appear to those skilled in the art from the present disclosure, this invention includes all features in the said disclosure which are novel over the prior art and which are not claimed in any separate application.

In the accompanying drawing, in which certain modes of carrying out the present invention are shown for illustrative purposes:

Fig. 1 is a rear view in elevation of a wall clock and shows the clock-supporting structure of the present invention organized therewith;

Fig. 2 is a vertical central-longitudinal sectional view, partly in elevation, of a wall clock of improved construction and arrangement, and the supporting-means forming part thereof, the said clock being shown engaged with a holding-screw and supported against a wall, these last two being indicated in broken lines; and

Fig. 3 is a perspective view of the drop-support of the improved supporting-structure.

The wall clock shown, and generally designated 30 by the reference character 10, is merely typical of wall clocks in which the invention to be described herein, may be embodied. For example, the present invention may be embodied to particular advantage in electric-motor-propelled wall clocks, or it may be usefully adapted to spring-driven wall clocks, and the said present invention may be used for wall clocks of either of the said types, which are of any preferred design or configuration.

In the example illustrated the wall clock 10 includes an outer enclosing-casing 11, which supports a bezel 12 on the front face thereof, the said bezel, in turn, carrying a crystal 13 therein. The bezel 12 and the crystal 13 form no part of the present invention and, as will be understood, hands or pointers, which may be of usual form, are arranged behind the said crystal on a conventional arbor, to turn about a regulation dial, these last named parts also forming no part of 50 the present invention and not being shown herein.

The said enclosing-casing 11 is shown generally square-shaped and, in the improved construction and arrangement of wall clocks of this invention, the said enclosing-casing is provided 55

with a circular opening 14, which extends therethrough and which includes an enlarged circular rear-recess 15. The wall of the casing 11, defining the said opening 14 and its enlarged rear-recess 15, comprises a relatively-thick body-portion 16, and a relatively thin tail-portion 17, the last enclosing the said rear-recess 15 of the said opening. The said casing 11 also includes an annular shoulder-portion 18 between the said relatively-thick body-portion 16 and the said relatively-thin tail-portion 17, which shoulder-portion forms the forward end-wall of the said rear-recess 15 and also provides a bearing-wall, as will hereinafter appear.

15 Mounted in the said opening 14 is a clock-movement, generally designated by the reference character 19. As is shown particularly well in Fig. 2, the clock-movement 19 includes a cup-shaped housing 20 and also includes a back-mounting-plate 21. Within the said housing 20 and forwardly of the back-mounting-plate 21, the operating parts of the said clock movement are arranged. The said operating parts comprise a gear-train of any desired arrangement and, in the case of electric clocks, also include a motor for driving the said gear-train. In Fig. 2, referred to above, part of the housing 20 is broken away to show certain of the said operating parts of the clock-movement 19. The movement housed within the housing 20 is supported at the rear thereof by pillars or screws 22 which, as shown, pass through the rear wall of the said housing and the mounting-plate 21 and are provided at the outside thereof, with securing-means, such as nuts 23.

In the preferred form of the invention, and as is also especially well shown in Fig. 2, the clock-movement 19 is mounted in the opening 14 between the front end thereof and the inner end of the rear-recess 15 of the said opening. As shown, the back-mounting-plate 21 of the said clock-movement closes the said opening 14 at the entrance of the said opening into its rear-recess 15. Preferably, the said back-mounting-plate is provided with a central body-portion 24, located in the opening 14, an integral offset-portion 25 inclined rearwardly with respect to the central body-portion 24, and an integral annular flange 26. The said integral annular flange 26 is spaced by the said offset-portion 25 rearwardly of the central body-portion 24 of the mounting-plate 21, and extends into the enlarged rear-recess 15 of the opening 14, and bears against the shoulder-portion 18 of the casing 11, forming the forward end-wall of the said rear-recess, to support the clock-movement 19 in place in the said casing.

A feature of the present invention is the provision of an improved supporting-structure, which is organized with the wall clock 10 for securing the said clock in place on a wall. As is contemplated herein, the above-described back-mounting-plate 21 also functions as part of the said supporting-structure and carries and supports means that are constructed and arranged to be brought down and about, and to receive and engage, a holding-device projecting from a wall. By way of expressing this last-named feature of the supporting-structure, the means whereby it is secured is termed herein a "drop-support," which is generally designated by the reference character 27 and will now be more particularly described.

Essentially, the said drop-support 27, which is organized with the mounting-plate 21 in a manner to be presently described, includes several in-

tegral portions, which respectively secure particular purposes of the functions of the clock-supporting structure of the present invention. As is especially well shown in Fig. 3, one of the said portions of the drop-support 27 is a mounting-strap 28. The mounting-strap 28 provides means for securing the drop-support 27 in place on the mounting-plate 21, and the said mounting-strap preferably includes a heel-portion 29, an intermediate co-operating offset-portion 30 and an upper-portion 31. The drop-support 27, as shown, also includes an integral extension-portion 32, and an integral attaching-clip or attaching-hook 33. The said integral extension-portion 32 extends rearwardly from the mounting-strap 28 of the drop-support and acts to rigidly support the said attaching-hook 33 in spaced relation to the said mounting-strap. In turn, the integral attaching-hook 33 depends from the said extension-portion 32, and the particular function of the said attaching-hook 33 is to receive and engage holding-means projecting from a wall, as will more fully appear hereinafter.

Referring now to the preferred relative arrangements of the structure of the wall clock 10, and particularly the supporting-structure thereof, these aspects of the present invention are particularly well shown in Fig. 2, in which the supporting-structure is shown in its organized relationship to the wall clock 10, and engaging a holding-screw 34 (shown in broken lines) projecting from a wall 35 (also shown in broken lines) to support the clock 10 in place on a wall.

As shown, the mounting-strap 28 engages the outer surface of the mounting-plate 21, which is spaced inwardly of the rear end of opening 14 in the casing. Preferably, the mounting-strap 28 is arranged within the said opening on the mounting-plate 21 above the axis of the said mounting-plate, and extends vertically upward thereon. In this arrangement, the heel-portion 29 of the mounting-strap engages with the central body-portion 24 of the mounting-plate in the opening 14, the intermediate co-operating offset-portion 30 engages with the offset-portion 25 of the mounting-plate 21, and the upper-portion 31 of the mounting-strap 28 engages with the annular flange 26 of the mounting-plate in the rear-recess 15 of the opening 14, and the said upper-portion 31 has its upper end located at the perimeter of the mounting-plate 21. In this position, the mounting-strap 28 is rigidly united with the mounting-plate 21, as by welding, soldering or brazing, or, if desired, by riveting. Preferably, and as shown, the mounting-strap 28 is rigidly secured to the mounting-plate 21, as by solder 36.

At the upper end of the said mounting-strap 28, the drop-support 27 is provided with a curved-portion 37 from which the said integral extension-portion 32 projects. This extension-portion 32 is arranged to extend substantially perpendicularly with respect to the vertically-extending mounting-strap 28, and it projects rearwardly therefrom in the rear-recess 15 adjacent to and preferably engaged by the said tail-portion 17 of the enclosing-casing 11. Preferably, too, the said extension-portion 32 is formed to correspond substantially in length to the length of the said tail-portion 17, and at the rear end of the said extension-portion, located at the rear end of the said recess 15, the said drop-support 27 is provided with a bend 38 from which the said integral attaching-hook 33 depends.

The said attaching-hook 33 is constructed and

arranged to be brought down and about, to receive and engage, holding-means, such as the holding-screw 34 projecting from a wall as, for example, the wall 35. For this purpose the said attaching-hook 33 is spaced rearwardly of the said mounting-strap 28 by the said extension-portion 32. The said extension-portion rigidly supports the attaching-hook 33, and it is reinforced by the overlying tail-portion 17 of the casing, and the said attaching-hook 33 depends from the said extension-portion 32, in substantial parallelism with the said mounting-strap 28, and within the said rear-recess 15, terminating therein substantially above the axis of the mounting-plate 21 on which the drop-support 27 is secured.

The said drop-support 27 is thus arranged in shielded and protected relation within the said rear-recess 15 of the clock-structure, and its attaching-hook 33 is provided with a receiving-recess 39 and flanking engaging-jaws 40-40, for receiving and engaging with holding-means, such as the holding-screw 34.

As is shown particularly well in Fig. 3, the said receiving-recess 39 opens downwardly and outwardly of the said attaching-hook 33 and extends upwardly therein, terminating in the upper part of the said attaching-hook. The spaced engaging-jaws 40-40 flank the said receiving-recess 39, and are integrally united about the upper terminal of the said receiving-recess in the said upper part of the attaching-hook 33.

Preferably, the adjacent side-edges 41-41 of the said flanking engaging-jaws 40-40 are tapered along the lower portions thereof to provide guide-edges 42-42, whereby the said receiving-recess 39 is provided with a flared-mouth 43. The said flared-mouth 43 provides wide unhampered entrance for a holding-device, such as the holding-screw 34. The tapered guide-edges 42-42 act to guide the attaching-hook 33 to bring the said holding-screw through the said flared-mouth and into a relatively-narrow portion of said receiving-recess 39. In the said relatively-narrow portion of the receiving-recess 39, the holding-screw 34 is engaged by the adjacent side-edges 41-41 of the flanking engaging-jaws 40-40, of said attaching-hook 33, to securely and reliably hold the wall clock 10 in place and, in the preferred arrangement, the drop-support 27, nested in the rear-recess 15 and shielded by the enclosing-casing 11, acts to support the clock 10 substantially flat against the wall 35.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A wall clock including in combination: a casing having an opening therethrough; a clock-movement mounted in the opening and surrounded longitudinally thereof by said casing; and supporting-structure including a back-mounting-plate for said clock-movement, and also including a substantially-rigid drop-support; the said drop-support including a mounting-strap extending vertically along said mounting-plate above the horizontal axis thereof and rigidly united therewith; and the said drop-support being

turned at the upper end of said mounting-strap to provide an integral extension-portion projecting rearwardly and substantially perpendicularly to said mounting-strap; said drop-support also being bent at the rear-end of said extension-portion to provide an integral attaching-hook depending from and rigidly supported by said extension-portion; the said attaching-hook depending in rearwardly-spaced relation to and in substantial parallelism with said mounting-strap and terminating above the said horizontal axis of said mounting-plate; and said attaching-hook being provided with a downwardly-opening receiving-recess flanked by engaging-jaws; whereby said attaching-hook may be brought down and about a holding-device projecting from a wall, said receiving-recess providing entrance for said holding-device and said flanking engaging-jaws fitting about said holding-device to securely support said clock adjacent said wall.

2. A wall clock including in combination: a casing having an opening therethrough; a clock-movement mounted in the opening and surrounded longitudinally thereof by said casing; and supporting-structure including a back-mounting-plate for said clock-movement spaced inwardly of the rear end of said opening; said supporting-structure also including a substantially-rigid drop-support; the said drop-support including a mounting-strap extending vertically along said mounting-plate above the horizontal axis thereof and rigidly united therewith within the said opening; and the said drop-support being turned at one end of said mounting-strap to provide an integral extension-portion projecting rearwardly in said opening and substantially perpendicularly to said mounting-strap; said drop-support also being bent at the rear-end of said extension-portion to provide an integral attaching-hook depending from and rigidly supported by said extension-portion, the said attaching-hook depending in rearwardly-spaced relation to and terminating above the said horizontal axis of said mounting-plate; and said attaching-hook being provided with a downwardly-opening receiving-recess flanked by engaging-jaws; whereby said attaching-hook may be brought down and about a holding-device projecting from a wall, said receiving-recess providing entrance for said holding-device and said flanking engaging-jaws fitting about said holding-device to securely support said clock adjacent said wall.

3. A wall clock including in combination: a casing having an opening extending therethrough; a clock-movement mounted in the opening and surrounded longitudinally thereof by said casing; and supporting-structure including a back-mounting-plate for said clock-movement, spaced inwardly of the rear-end of said opening; said supporting-structure also including a substantially-rigid drop-support; the said drop-support including a mounting-strap extending vertically along said mounting-plate above the horizontal axis thereof and rigidly united therewith within said opening; the upper end of said mounting-strap being located at the perimeter of said mounting-plate and being turned thereof to provide an integral extension-portion, the said extension-portion projecting substantially perpendicularly to said mounting-strap and rearwardly in said opening adjacent the top-portion of the wall thereof; the said drop-support also being bent at the rear-end of said extension-portion to provide an integral attaching-hook depending from and rigidly supported by said extension-

portion; the said attaching-hook depending in rearwardly-spaced relation to and in substantial parallelism with said mounting-strap and terminating above the said horizontal axis of said 5 mounting-plate; and said attaching-hook being provided with a downwardly-opening receiving-recess flanked by engaging-jaws; whereby said attaching-hook may be brought down and about a holding-device projecting from a wall, said receiving-recess providing entrance for said holding-device and said flanking engaging-jaws fitting about said holding-device to securely support 10 said clock adjacent said wall.

4. A wall clock including in combination: a 15 casing having an opening extending therethrough; a clock-movement mounted in the opening and surrounded longitudinally thereof by said casing; and supporting-structure comprising a shielded drop-support substantially arranged in 20 said opening; said drop-support including a mounting-portion secured to a portion of the said wall clock at the rear thereof, and also including an attaching-hook depending substantially within said opening in rearwardly spaced 25 relation to said clock-movement and terminating above the horizontal axis thereof; the said attaching-hook including a vertically-extending receiving-recess opening downwardly thereof and also including spaced engaging-jaws flanking said 30 receiving-recess; the lower portions of adjacent side-edges of the flanking engaging-jaws being tapered, to provide guide-edges, and to also provide a flared-mouth for said receiving-recess; whereby said attaching-hook may be brought 35 down and about a holding-device projecting from a wall, said flared-mouth and guide-edges providing wide and guided entrance for said holding-device into a relatively-narrow portion of said receiving-recess for engagement with said engaging-jaws.

40 5. A wall clock including in combination: a casing having an opening extending therethrough; a clock-movement mounted in the opening and surrounded longitudinally thereof by said 45 casing; and supporting-structure including a back-mounting-plate for said clock-movement, spaced inwardly of the rear-end of the opening in the said casing; said supporting-structure also including a shielded substantially-rigid drop-support substantially arranged within the opening 50 in the casing; the said drop-support including a mounting-strap extending vertically along said mounting-plate above the horizontal axis thereof and rigidly united therewith within the opening 55 in the said casing; the upper end of said mounting-strap being located at the perimeter of said mounting-plate and being turned thereat to provide an integral extension-portion; the said extension-portion projecting substantially perpendicularly to said mounting-strap and rearwardly in the opening in the said casing adjacent the top-portion of the wall thereof, and the said extension-portion having its rear-end terminat- 60

ing at the rear-end of the opening in the said casing; the said drop-support also being bent at the said rear-end of said extension-portion to provide an integral attaching-hook depending from and rigidly supported by said extension-portion; the said attaching-hook depending substantially within the opening in the said casing in rearwardly spaced relation to and in substantial parallelism with said mounting-strap and terminating above the said horizontal axis of said 10 mounting-plate; and said attaching-hook being provided with a downwardly-opening receiving-recess flanked by engaging-jaws; whereby said shielded drop-support may be brought down to position its attaching-hook about a holding-device projecting from a wall, said receiving-recess providing entrance for said holding-device and said flanking engaging-jaws fitting about said holding-device to securely support said wall clock substantially-flat against said wall.

20 6. A wall clock including in combination: a casing having an opening extending therethrough; a clock-movement mounted in the opening and surrounded longitudinally thereof by said casing; and supporting-structure including a 25 back-mounting-plate for said clock-movement spaced inwardly of the rear-end of said opening; said supporting-structure also including a substantially-rigid drop-support; the said drop-support including a mounting-strap extending vertically along said mounting-plate above the horizontal axis thereof and rigidly united therewith within the opening; and the upper end of said mounting-strap being located at the perimeter of said mounting-plate and being turned thereat 30 to provide an integral extension-portion; the said extension-portion projecting substantially perpendicularly to said mounting-strap and rearwardly in the opening adjacent the top-portion of the wall thereof; the said drop-support also 35 being bent at the rear-end of said extension-portion to provide an integral attaching-hook depending from and rigidly supported by said extension-portion, the said attaching-hook depending in rearwardly spaced relation to and in substantial parallelism with said mounting-strap, and terminating above the said horizontal axis of said mounting-plate; the said attaching-hook including a vertically-extending receiving-recess 40 opening downwardly thereof, and also including spaced engaging-jaws flanking said receiving-recess; the lower portions of adjacent side-edges of the flanking engaging-jaws being tapered, to provide guide-edges and to also provide a flared-mouth for said receiving-recess; whereas said 45 attaching-hook may be brought down and about a holding-device projecting from a wall, said flared-mouth and guide-edges providing wide and guided entrance for said holding-device into a relatively-narrow portion of said receiving-recess 50 for engagement with said engaging-jaws.
